ADJUSTABLE HOLDER FOR LIPSTICKS AND THE LIKE

Howard F. Reichenbach and Albert N. Stadalius,
Waterbury, Conn., assignors to The Chase
Companies, Incorporated, Waterbury, Conn., a
corporation of Connecticut

Application May 28, 1936, Serial No. 82,166

5 Claims. (Cl. 206—56)

This invention relates to an improvement in adjustable holders for lipsticks, shaving soaps, etc., etc.

In certain types of adjustable lipstick holders as heretofore produced there is employed an advanceable and retractable lipstick elevator or carrier which has been actuated by a rotatable split operating-sleeve. In this type of construction it often happens that when the carrier or elevator is retired to the limit of its inward movement a user will inadvertently continue turning the operating-member, with the result that the operating-sleeve is often forced out of the body of the lipstick.

One of the main objects of the present invention is to provide a simple, reliable, adjustable holder for lipsticks in which the difficulties referred to above are overcome.

Another object is to provide an adjustable holder of the character referred to in which the connection between the body-member and operating-sleeve is effectively concealed, to thus enhance the appearance of the holder.

A further object of the present invention is to provide a superior adjustable holder suitable for use in connection with lipsticks, etc., and characterized by ease of assembly and superior resistance to accidental or unintentional disassembly.

With the above and other objects in view, as will appear to those skilled in the art from the following, considered in conjunction with the accompanying drawing and appended claims, the present invention includes all features disclosed therein which are novel over the prior art.

In the accompanying drawing:

Fig. 1 is a view in side elevation of a lipstick holder embodying the present invention;

Fig. 2 is a view looking toward the outer end 40 thereof;

Fig. 3 is a broken view in side elevation with a portion of the body-member broken away and in section;

Fig. 4 is a central longitudinal sectional view 45 taken on the line 4—4 of Fig. 1;

Fig. 5 is a transverse sectional view taken on the line 5—5 of Fig. 3;

Fig. 6 is a similar view taken on the line 6—6 50 of Fig. 3;

Fig. 7 is a view in side elevation of the operating-unit, comprising the operating-sleeve and its operating-head;

Fig. 8 is a view of the body-member and operating-member illustrating the mode of collapsing

the outer end of the operating-sleeve to effect its insertion into the body-member; and

Fig. 9 is a transverse sectional view taken on the line 9—9 of Fig. 8.

The particular adjustable lipstick holder herein chosen for illustration includes a tubular body-member 10 which may be molded from materials such, for instance, as bakelite, urea-formaldehyde, etc. The said body-member is open at each of its respective opposite ends and is formed in 10 its interior with a steep-pitch helical groove 11 receiving the head 12 of a rotary coupling-pin 13 mounted in a cup-shaped carrier or elevator 14. The said coupling-pin 13 is supported for 15 rotary movement at 15 in the side wall of the carrier 14 and adjacent its opposite end it is also supported for rotary movement in a bearing-finger 16 bent up from the bottom or end wall 17 of the carrier.

The head 12 of the coupling-pin 13 above referred to extends through a longitudinal slot 18 formed in the cylindrical side wall 19 of a relatively-deep cup-shaped operating-sleeve or member generally designated by the numeral 20 and preferably formed of springy material such, for instance, as spring-brass. The bottom wall 21 of the said operating-sleeve is perforated to fit over a tubular rivet 22 which is formed integrally with a disk-shaped metallic operating-head 23, the upper face of which latter bears tightly 30 against the under face of the bottom wall 21. The said operating-head is rigidly attached to the operating-sleeve 20 by upsetting the upper end at 24 of the said rivet over a washer 25, which latter is thus pinched between the portion 35 24 of the rivet and the upper face of the bottom wall 21, as clearly shown in Fig. 4.

The upper end of the longitudinal slot 18 in the operating-sleeve 20 ends a short distance inward of the outer end of the said sleeve. The extreme upper or outer end of the operating-sleeve 20 is turned outward to form a retaining-flange or shoulder 26 which is adapted to engage with an annular outwardly-facing retaining-shoulder 27 formed within the body-member 10 40 just below the outer end thereof.

The material of the operating-sleeve 20 lying between its outer end and the outer end of the slot 18 therein is severed or parted along a line 28 which results in the formation of two opposed locking-fingers 29—29 which are adapted to abut along the said line 28 under conditions as will be hereinafter described. The locking-fingers 29—29 also serve to limit the outward movement of the carrier or elevator 14, owing 45 50 55

to the engagement of their inner edges (constituting the outer end of the slot 18) by the head 12 of the coupling-pin 13.

The retaining-flange 26 of the operating-sleeve 20 is formed upon the latter before its assembly with the body-member 10, and to permit the introduction of the operating-sleeve into the body-member, the locking-fingers 29-29 are brought into overlapping relationship, as indicated in Figs. 8 and 9. After the outer end of the operating-sleeve 20 is collapsed and introduced into the body-member 10 as just referred to, the introductory movement of the said operating-sleeve is continued until its retaining-flange 15 comes to a position very slightly beyond the retaining-shoulder 27 of the said body-member. The resiliency of the operating-sleeve will now snap the retaining-flange outwardly for engagement with the retaining-shoulder 27, with the result that the locking-fingers 29-29 will move out of their overlapping relationship into which they have been previously sprung and their opposed vertically-extending edges will snap into line so that the retaining-flange 26 can not be disengaged 20 from the retaining-shoulder 27 without first deliberately overlapping the said locking-fingers.

By turning the operating-head 23 and hence the operating-sleeve 20 in one direction while holding the body-member 10 stationary, the carrier elevator 14 may be advanced toward the outer end of the holder to project a lipstick carried thereby outwardly for use. By turning the operating-head 23 in a reverse direction relative to the body-member 10, the said carrier may be withdrawn into the operating-sleeve 20 until its bottom wall 19 abuts against the internal rivet 24 of the said operating-head 23. When the carrier abuts against the rivet 24 as just described, any continued turning movement of the operating-head 23 will tend to longitudinally force the operating-sleeve 20 out of the body-member 10. This tendency is resisted by the engagement of the retaining-flange 26 with the retaining-shoulder 45 27, though the strain thus applied tends to collapse the outer end of the operating-sleeve 20 to permit the retaining-flange 26 to slip off of the retaining-shoulder 27. However, before the retaining-flange 26 can be disengaged from the retaining-shoulder 27, the opposed longitudinal edges of the locking-fingers 29-29 will abut and prevent the appreciable contraction of the outer end of the operating-sleeve and thus prevent the said operating-sleeve from being withdrawn from the 50 body-member 10.

Among other advantages achieved by the construction and arrangement of parts described, it is to be noted that it is possible to locate the retaining-flange 26 of the operating-sleeve 20 at 55 a point below the outer end of the body-member 10, so that the appearance of the holder is very much enhanced. Furthermore, the annoyance of having the operating-sleeve unintentionally forced out of the body-member 10 is avoided 60 without requiring either complex or costly expedients.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended 70 to be embraced therein.

We claim:

1. An adjustable holder for lipsticks and the like including in combination: a tubular body-member; an advanceable and retractable carrier within the said body-member; and a tubular operating-member within the said body-member and rotatable with respect thereto to advance and retract the said carrier; the said operating-member having a collapsible portion provided with a retaining-projection engaging with a portion of the said body-member to hold the two said members against relative axial displacement, the said operating-member also having releasable locking-means serving to normally prevent the collapse of its collapsible portion. 10

15 2. An adjustable holder for lipsticks and the like including in combination: a tubular body-member; an advanceable and retractable carrier within the said body-member; and a tubular operating-member also within the said body-member and rotatable with respect thereto to advance and retract the said carrier; the said operating-member being provided with a retaining-projection engageable with a portion of the said body-member to hold the two said members against relative axial displacement, the portion of the said operating-member adjacent the said retaining-projection being slotted to permit the portions adjacent the slit to be collapsed into overlapping relationship, and providing opposed edges which 30 are adapted to abut one against the other to normally prevent such collapsing.

3. An adjustable holder for lipsticks and the like including in combination: a tubular body-member; an advanceable and retractable carrier 35 within the said body-member; and a tubular operating-member also within the said body-member and rotatable with respect thereto to advance and retract the said carrier; the said operating-member being provided at its outer end with a retaining-projection engageable with a portion of the said body-member to hold the two said members against relative axial displacement, and the outer end of the said operating-member being slotted to permit its being collapsed and providing opposed edges which are adapted to abut one against the other to prevent such collapsing, the portions of the operating-member lying adjacent to said opposed edges also being adapted to be brought into overlapping relationship to permit 50 the contraction of the outer portion of the said operating-member.

4. An adjustable holder for lipsticks and the like including in combination: a tubular body-member; an advanceable and retractable carrier 55 within the said body-member; and a tubular operating-member also within the said body-member and rotatable with respect thereto to advance and retract the said carrier; the said operating-member being provided at its outer end with an 60 outturned retaining-flange engageable with a portion of said body-member to hold the two said members against relative axial displacement, the outer end of the said operating-member also being cut away to provide opposed complementary locking-fingers adapted to be sprung into overlapping relationship to collapse the outer end of the said operating-member, the opposed edges of the said locking-fingers being also adapted to 65 abut one against the other to prevent such collapsing. 70

5. An adjustable holder for lipsticks and the like including in combination: a tubular body-member formed of molded composition and hav- 75

ing an interior retaining-ledge or shoulder located within its outer end and also being formed in its interior with a helical groove; a tubular operating-member rotatably mounted within the 5 said body-member and having an inwardly-yielding retaining-flange engaging with the retaining-ledge or shoulder of the said body-member, the said tubular operating-member also being provided with releasable locking means preventing 10 its retaining-flange from yielding inwardly out

of engagement with the retaining-ledge or shoulder of the said body-member; and an advanceable and retractable carrier within said tubular operating-member and having a portion engageable with both the operating-member and the body-member to be advanced and retired by relative rotary movement between the said members. 5
